UNITED STATES PATENT OFFICE.

MATHILDE EHRLICH, OF VIENNA, AUSTRIA-HUNGARY.

PAPER SERVING OR DISTRIBUTING DEVICE.

No. 888,072.

Specification of Letters Patent.

Patented May 19, 1908.

Application filed October 16, 1906. Serial No. 339,166.

To all whom it may concern:

Be it known that I, MATHILDE EHRLICH, of Obere Donaustrasse 63, Vienna, in the Empire of Austria-Hungary, spinster of no occupation, having invented certain new and useful Improvements in Paper Serving or Distributing Devices, do hereby declare that the following is a full, clear, and exact description of the same.

10 This invention relates to a device for serving or distributing paper.

The object of the invention is to increase the utility of the paper distributor, besides decreasing its bulk owing to the fact that the 15 sheets are folded into the smallest possible space.

The sheets of paper to be used in the case are each preferably folded in zig-zag order in four approximately equal parts, the two 20 middle laps forming a fold which incloses the end portion of the succeeding sheet, whereby when the third quarter of one sheet is being withdrawn it will draw out the first quarter of the succeeding sheet which rests on it.

25 In order that the arrangement may be clearly understood, I will proceed to describe the same with reference to the drawing accompanying this specification, which illustrates the device by a perspective view.

30 My device comprises a case or receptacle 1, of rectangular shape and adapted to receive the sheets of paper, 4, seen in dotted lines.

The top of the case is provided with a narrow slot 2, through which projects the upper 35 bent end of a forked suspensory device 3, the arms 8 of which are bent at right angles to form a portion upon which rest the pile of paper sheets 4 said portion being constituted by the bent ends 9 of the device 3. The top 40 of the case is also provided near the edge opposite to where the slot 2 is located with a slot 5, through which the sheets of paper are withdrawn.

The bent end of the suspensory device 3 45 enables the same to be hooked over a nail or the like provided in a wall.

When a number of sheets have been withdrawn from the case, if the case does not sink down through its own weight on account of the space left between the top of the sheets 50 and the slot, and the end of the next sheet does not project fully from the slot, then the case should be pulled down slightly by means of the cord or string 6 hanging from the bottom thereof, so that a greater part of the fork 3 is 55 visible and the sheets come nearer to the slot 5.

This case possesses the advantage that it can be made of simple paper and that the sheets can be very easily withdrawn from above.

60 Instead of the fork, a depending member can be formed of cardboard or other suitable material bent for the reception of the pile of paper sheets.

What I claim and desire to secure by Letters Patent of the United States, is:

1. In a paper serving device, the combination with a receptacle for paper sheets, provided with a slot through which the sheets may be withdrawn, of a suspending device 70 arranged within the receptacle and adapted to support the sheets, said suspending device and receptacle being arranged for movement relatively to each other.

2. In a paper serving device the combination with a receptacle for paper sheets, provided with a slot through which the sheets may be withdrawn, of a suspending device arranged within the receptacle and having one end projecting through a slot in the receptacle and its opposite end bent to form a portion upon which the sheets are piled, said suspending device and receptacle being arranged for movement relatively to each other.

85 In testimony whereof I affix my signature in presence of two witnesses.

MATHILDE EHRLICH.
